UNITED STATES PATENT OFFICE

2,610,593

SKYLIGHT CONSTRUCTION

Max Wasserman, Chestnut Hill, Mass.

Application November 3, 1950, Serial No. 193,897

5 Claims. (CL. 108—16)

1

The present invention relates to skylights and is adaptable for most any type of skylight of whatever nature or description.

The skylight of the present invention is particularly easy to install, can be readily formed to fit any shape or size of skylight opening, is comparatively inexpensive, and is durable and strong.

The present invention preferably uses a transparent or translucent plastic material in place of the usual glass member and one of the chief features of the invention is that the plastic element is formed to fit the frame which is mounted on the skylight opening.

The invention can be applied quite as readily to new building constructions as to old, and is easily adaptable for all sizes and shapes of skylight openings. Further it is extremely strong because of its construction and is completely waterproof without the addition or the using of waterproof compounds after the skylight has been installed.

The present invention will be more fully understood from the description in the specification annexed hereto when taken in connection with the drawings illustrating an embodiment of the same, in which:

Figure 1 shows a broken section in elevation through the skylight, and

Figure 2 shows a plan view of the same.

In the arrangement indicated in Figure 1, the invention is shown in connection with a frame opening which employs wooden beams but it may be applied to frame openings of other materials. Figure 1 shows sectional beams 1 and 2 and the non-sectioned beam 3 forming the skylight opening. These beams are covered over the top and sides both inside and out by a metal channel member 4 made of galvanized sheet metal, other metal elements or other materials sufficiently durable to withstand weather and strong enough to act as a support for the skylight covering element. The channel member 4 has a cross section which provides a wall 5 on the outside of the wooden frame, a covering web 6 on the top edge or sill of the wooden frame and an inner wall element 7 inside of the wooden frame which extends both downward into the skylight opening and upwards providing the upwardly extending flange 8. In addition to this the element 4 has an outwardly extending flange member 9 which may be continuous with the top plate or covering 6 of the edge of the beam either in a horizontal or in a downwardly sloping direction. Within the outer wall section 5, a base 55

2

flashing 10 may be included which extends upward to the top cover section 6. Covering the external flange member 9 may be a gasket 11 and over this is fitted a plastic dome 12 which has a horizontal flange 13 resting securely around the whole flange 9 and gasket 11. The cover is secured and held in place by means of a series of bolts 15 extending from the top of the plastic flange through holes 15' in the plastic aligned with corresponding holes in the metal through which the bolts pass. These bolts are capped tightly by the nut 16 on the inside of the flange 9. The bolts may fit closely in the metal flange but the holes 15' in the plastic are large enough to allow lee-way for expansion and movement of the bolts 15 in the holes. A gasket 14 may be used under the bolt head or a complete gasket may be cemented to the top of the plastic flange 13. A large size washer 17 should be placed beneath the head of the screw 15 over the gasket 14. The plastic skylight itself may be formed of various thicknesses of material. For a 30" skylight, a 1/8 clear "Plexiglas" is satisfactory. The dome is preferably molded, formed or blown to size in any suitable and well-known manner.

It will be noted from the drawing of Figure 1 that the covering gasket 11 is open at the corners in the region 18, but the flat surface 6 of the top channel covering the skylight frame is mitered and fitted at a 45° angle and these edges are soldered together along their whole length so that no water will get beneath them. By cutting the gasket away at the square corner section any moisture or water which might gather under the corners will readily flow out. For this purpose the corners may slightly slope for drainage purposes.

The flange 8 extends upwards from the top of the horizontal surface 6 providing a gutter-like element to hold any water which may form from frost and ice and permit it ultimately to drain to the outside of the skylight. The channel sections 4 are cut and mitered to the desired length for the skylight frame and since the beams are usually approximately 2" on end, a single type channel section will be satisfactory for practically all purposes. The plastic skylight may be formed to the desired shape and size established when the channel has been fitted. The channel may be held to the frame of the skylight in any suitable manner as by screws 20 applied through the inside lower section of the inner wall 7.

In the arrangement of Figure 1, if the base flashing 10 is carried over on top of the skylight sill, the outer wall 5 may be replaced by a few de-

pendent sections overlying the flashing 10 or even these dependent sections of the wall 5 may be omitted where the sections of the whole metal frame structure are joined as a substantially integral rigid frame. In this latter construction the inner dependent walls 7 which may also be replaced by a number of downwardly dependent fingers will lock the whole frame in place and thereby prevent any sidewise displacement.

It will also be noted that where the flange 13 of the dome is tightly held to the outwardly extending flange 9 by means of the gasket 11 so as to make a water-tight joint, the upwardly extending wall section 8 may be omitted.

While these various changes may be employed with good results, the specific construction previously described and shown in the drawings is the preferred form.

Having now described my invention, I claim:

1. A covering for a sky light opening having a sill framing the sky light opening, a metallic frame extending all around the sill on the top edge thereof with an outwardly projecting flange all around the sky light opening, means extending downwardly from the inner edge of the frame for securing the metallic frame to said sill, a plastic dome member having a base flange coextensive with said outwardly projecting metallic flange all around the sky light opening, and means for clamping said flanges together including a plurality of spaced bolts passing through aligned holes in the flange of the plastic dome and said metal flange, the holes in the plastic dome being slightly larger in diameter than the bolts which pass through them, providing fitting and expansion tolerances.

2. A skylight construction for a building opening having a raised sill about the periphery of said opening, comprising a covering frame for said sill having a downwardly extending flange about the outer side of the sill and an upwardly extending flange of said covering frame at its inner side, said covering frame also having a flange extending outwardly of said covering frame, a preformed plastic dome-shaped cover having a marginal flange coextensive and fitting to the outwardly extending flange, means securing said cover at its marginal flange to the outwardly extending flange and means securing said covering frame to the sill.

3. A skylight construction for a building opening having a raised sill about the periphery of said opening comprising a covering frame for said sill having downwardly extending flanges about the outer and inner sides of the sill and an upwardly extending flange of said covering frame at its inner side, said covering frame also having a flange extending outwardly of said cov-

ering frame, a preformed plastic dome-shaped cover having a marginal flange coextensive and fitting to the outwardly extending flange, means securing said cover at its marginal flange to the outwardly extending flange and means securing said covering frame to the sill.

4. A skylight construction for a building opening having a raised sill about the periphery of said opening comprising a covering frame for said sill having a downwardly extending flange about the outer side of the sill and an upwardly extending flange of said covering frame at its inner side, said covering frame also having a flange extending outwardly of said covering frame, a preformed plastic dome shaped cover having a marginal flange coextensive and fitting to the outwardly extending flange, a sealing gasket between the marginal flange and the outwardly extending flange, said gasket being omitted in selected areas about the marginal flange, means securing said cover at its marginal flange to the outwardly extending flange, and means securing said covering frame to the sill.

5. A skylight construction for a building opening having a raised sill about the periphery of said opening comprising a covering frame for said sill having downwardly extending flanges about the outer and inner sides of the sill and an upwardly extending flange of said covering frame at its inner side, said covering frame also having a flange extending outwardly of said covering frame, a preformed plastic dome-shaped cover having a marginal flange coextensive and fitting to the outwardly extending flange, means securing said cover at its marginal flange to the outwardly extending flange and means securing said covering to the sill, in the downwardly extending flange about the inner side of the sill.

MAX WASSERMAN.
